UNITED STATES PATENT OFFICE

109,132

DESIGN FOR A SHOE

Edward Freeman, Dorchester, Mass., assignor to Hubbard Shoe Co., Inc., Rochester, N. H., a corporation of New Hampshire

Application December 20, 1937, Serial No. 73,760

Term of patent 3½ years

To all whom it may concern:

Be it known that I, Edward Freeman, a citizen of the United States, residing at Dorchester, in the county of Suffolk and Commonwealth of Massachusetts, have invented a new, original, and ornamental Design for a Shoe, of which the following is a specification, reference being had to the accompanying drawing, forming a part thereof, in which,

Fig. 1 is a plan view of a shoe embodying my new design, and

Fig. 2 is a view of the shoe in side elevation, the heel being shown conventionally in dotted lines.

I claim:

The ornamental design for a shoe substantially as shown and described.

EDWARD FREEMAN.
